CLAIM

The ornamental design for a pet toy ball as shown and described.

DESCRIPTION

FIG. 1 is a perspective view of a first embodiment of a pet toy ball with three straps.

FIG. 2 is a front view of the pet toy of FIG. 1.

FIG. 3 is a rear view of the pet toy of FIG. 1.

FIG. 4 is a left side view of the pet toy of FIG. 1.

FIG. 5 is a right side view of the pet toy of FIG. 1.

FIG. 6 is a top view of the pet toy of FIG. 1.

FIG. 7 is a bottom view of the pet toy of FIG. 1.

FIG. 8 is a perspective view of a second embodiment of a pet toy ball with one strap.

FIG. 9 is a perspective view of a third embodiment of a pet toy ball with two straps.

FIG. 10 is a perspective view of a fourth embodiment of a pet toy ball with four straps.

FIG. 11 is a perspective view of a fifth embodiment of a pet toy ball with five straps.

FIG. 12 is a perspective view of a sixth embodiment of a pet toy ball with six straps.

FIG. 13 is a perspective view of a seventh embodiment of a pet toy ball with seven straps; and,

FIG. 14 is a perspective view of an eighth embodiment of a pet toy ball with eight straps.

The broken lines illustrate portions of the pet toy ball that form no part of the claimed design.

1 Claim, 14 Drawing Sheets
